United States Patent Office.

JAMES B. CLEVELAND AND HENRY C. GULDERSLEIN, OF HACKENSACK, NEW JERSEY.

Letters Patent No. 92,424, dated July 13, 1869.

IMPROVEMENT IN MACHINE FOR SETTING, FITTING, AND TEMPERING SPRING-PLATES.

The Schedule referred to in these Letters Patent and making part of the same.

To all whom it may concern:

Be it known that we, JAMES B. CLEVELAND and HENRY C. GULDERSLEIN, of the town of Hackensack, in the county of Bergen, and State of New Jersey, have invented certain new and useful Improvements in Machinery for Setting or Fitting Springs or Spring-Plates for Carriages, or other uses; and we hereby declare the following to be a full, clear, and exact description thereof, reference being had to the accompanying drawings, which are lettered to correspond with and form a part of this specification.

In order that the public may fully understand the nature of our invention, and those who are acquainted with the manufacture of carriage or elliptic springs be enabled to construct the same, we will describe it as follows, to wit:

Figure 1 is a perspective drawing of that portion of our apparatus employed for setting, shaping, and tempering the backs or bed-plates of carriage or elliptic springs.

A is an adjustable die, formed of two pieces, and separated by two or more screw-bolts *s s*, to allow the water to be poured upon the metallic back-plate *N*, while being formed and held into shape between the flanges *r r* of the movable die *A* and stationary die or bed *A'*, which is also made in two separate longitudinal plates, to be opened or closed by the set-screws *s' s'*, to correspond with and receive any desirable width of back-plates *N*, between the flanges of the stationary bed *A'*.

L is a foot-lever, or treadle, which operates the adjustable or upper die *A*, and holds the same firmly upon the back-plate *N* during the process of shaping and tempering said back *N*.

Figure 2 represents a perspective view of that portion of our invention employed to fit the lesser plates or lifts of the spring to the backs or larger plates, by first placing the bottom or first lift upon the back *N*, already shaped and tempered, as shown at fig. 1, then passing the two together through the rollers *R R'*, which shape the lift-plate to correspond with and fit upon the back *N*.

The lower roller *R'* moves in a vertical slot, up or down, when operated by means of the foot-lever or treadle *M*.

The plates and lifts are placed upon the vertical pillars 1, 2, 3, 4, and 5, which are so arranged that the pillar 3 is sufficiently elevated to support the curved plates, and prevent their springing out of shape when pressed upon by the upper section *o* of the plate or lift-tempering machine.

The adjustable head *o* is also made with an opening or openings to allow the water to pass through it on the plate or lift *N*.

This adjustable head or fall *o* is operated by a foot-

lever, in a similar manner to fig. 1, and is constructed in two parts or longitudinal plates, which are adjusted to meet the different widths of spring-plates by means of set-screws, *s' s'*, and are provided with bearings or pillars 1', 2', 3', 4', 5', arranged so that 3' is shorter than the others, so as to press upon the convex surface, or upper side of the lifts *N'*, without springing the plates while holding them into shape upon the backs *N*, or next larger plates or lifts, by means of projecting flanges *u u*, which may be either upon the top of the stationary supports or pillars 1, 2, 3, 4, 5, or upon the adjustable bearings, as shown in the drawings, for holding the plates into shape while tempering the same for use.

P is a parallel horizontal press operated by the lever *e*, to straighten the sides or broad surfaces of the spring-plates *N N'*.

Also the vertical lever-press *e'* is employed to straighten the edges of the plates when operated by any suitable power.

We do not confine ourselves to any length of plates, as our dies or presses are made to be adapted to the different lengths and widths of spring-plates.

The superiority of the above mode of forming and fitting the plates in presses or dies, and tempering said plates while in the dies, thereby rendering them ready for use, without using the edge of the hammer to bring them into shape, thus saving the time required to grind out the hammer-marks, as is the case when the backs and lifts are tempered by the old mode is evident; hence we are enabled to fit, set, and temper as many plates in two hours as would require the labor of one man for ten hours by the old process.

We do not claim to have invented adjustable beds composed of vertical bars or strips, for the purpose of forming carriage or elliptic springs; neither do we claim concave beds, provided with grooves for the reception of water by means of injecting-tubes, or any other device that will keep the centre or middle of the plate or lift submerged in water while the ends of the plate are untempered, and the middle portion of the lift becomes too hard and brittle for good work.

Finally, we do not claim vibrating bars with rollers of any kind, in combination with concave beds for the purpose of forming elliptic spring-plates; neither do we employ hollow rollers (perforated) for the purpose of filtering water upon the steel plates, as all of the above, in our opinion, are of little value in forming or tempering plates. Consequently the nature of our invention consists in the construction and application of a double horizontal transverse adjustable former *A* and *A'*, having an open back, *B*, (through which the plate or lift *N* is tempered to any required hardness, in combination with a double convex bed *A''* and *A'''*, which is also formed in two parts, horizontally adjusted,

to receive and hold the lift or plate N, similar to former A and A² by means of set screws s and flanges r. Therefore,

What we claim as our invention, and believe to be new and useful to the public, is—

The adjustable double former A and A², figs. 1, 3, 4, having an open back or space, B, and flanges, r, in combination with an adjustable convex bed, constructed in two parts A' and A'', all arranged and operating in

the manner and for the purpose substantially as above set forth.

In testimony whereof, we hereunto subscribe our names, in the presence of two witnesses.

JAMES B. CLEVELAND.

HENRY C. GUILDESSLEIN.
